MAGAZINE OR THE LIKE

George Heller, Englewood, N. J., assignor of one-half to Henry M. Herbener, Thomasville, Ga.

Original application November 10, 1941, Serial No. 418,617. Divided and this application June 13, 1942, Serial No. 446,925

10 Claims. (Cl. 281—25)

My invention is a method of reinforcing the printed sheets or covers of magazines or the like, at their engagement with the staples, which hold the same together, and the product produced by the method.

The ordinary magazine includes a cover and a number of superposed leaves. Both the cover and the leaves are usually printed on both sides. Both the cover and the leaves are formed of continuous paper sheets which are folded transversely upon themselves and are secured together adjacent to the folding line by staples.

It not infrequently happens that the cover is torn from the body of the magazine, or individual sheets are torn from the magazine, by the lifting of the magazine by the cover or the individual sheets, or by other manipulation.

In accordance with my method a reinforcing coating is applied or printed upon the cover sheet and the leaf sheet or sheets, at proper positions thereon. The coating provides coated reinforced area or areas, at the folding lines of the sheets which areas are stronger and tougher than the sheets alone, and the staples pass through these reinforced coated areas. The result is that the cover sheet or leaf sheet or sheets are more securely held in place by staples. The coating material used is one which may be applied to the sheet or sheets by a printing process during the printing of the magazine and therefore must set rapidly. It is preferred to use a thermoplastic material as a coating, although a rapidly drying volatile plastic material may be used. The thermoplastic material will set instantly upon the removal of heat. As illustrations of thermoplastic materials, I may employ uncured rubber which is compounded with curing ingredients and anti-oxidants or uncured rubber treated with an anti-oxidant. As a highly volatile coating material I may use celloidin dissolved in an alcohol ether mixture or collodion dissolved in the same mixture. The coating material used, whether thermoplastic or rapidly volatile, should preferably be of such a character that it will produce a coating which is flexible, tough, and possesses substantial tensile strength.

This application is a division of my co-pending application for Method for producing magazine and product produced thereby, filed November 10, 1941, Serial No. 418,617.

In the accompanying drawing forming a part of this application and in which like numerals are employed to designate like parts throughout the same,

Figure 1 is an inner or front elevation of the

sheet constituting the cover of the magazine, showing the coated reinforced areas formed thereon,

Figure 2 is an elevation of the back or outer face of the sheet from which two of the leaves of the magazine are formed, showing the coated reinforced areas formed thereon,

Figure 3 is a perspective view of the magazine, embodying the assembled cover and leaf sheets,

10 Figure 4 is an enlarged transverse section taken on line 4—4 of Figure 3,

Figure 5 is a diagrammatic view illustrating the method of printing the coating upon the sheets during the printing of individual pairs of connected leaves, and,

Figure 6 is a view similar to Figure 4, showing a slight modification of the magazine.

In the drawing, wherein for the purpose of illustration is shown a preferred embodiment of my invention, the numeral 10 designates the cover sheet of the magazine, which cover sheet is foldable upon a transverse line 11, providing cover leaves 12. This cover sheet has a reinforcing coating 13 applied to its front or inner face, adjacent to the folding line 11. The coating 13 is preferably in the form of elongated or elliptical areas, providing with the sheet reinforced coated areas 13' of the same shape and size as the coating. These reinforced coated areas 13' straddle the folding line 11 and staples 14 pass through the reinforced coating areas 13'. The coating 13 is also applied to the leaf sheet 15. The coating is applied to the outer or back face of each leaf sheet, at the folding line 11' and straddles this folding line. This is preferred so that the coating will not be visible upon the inner face of the center leaf sheet, which is usually employed to carry a full-page advertisement. The coating 13 upon the leaf sheet 15 provides reinforced coating areas 13', corresponding in shape and size with the coating 13. The leaf sheet when folded upon its transverse line 11' produces the leaves 15'. The reinforced coated areas of the leaf sheet 15 straddle the folding 11', as shown. As clearly shown in Figure 4, the reinforced coating areas 13' are arranged in spaced groups, and the areas in each group are in substantial alignment, and the staples 14 pass through the reinforced coated areas and the ends 50 of the staples are bent down over the center leaf, as shown.

As stated, the plastic material is printed upon the sheet to provide the coating. When a thermoplastic material is used, such thermoplastic material is kept in a molten condition in a tank

16 which is suitably heated. An applicator roll 17 applies the heated molten thermoplastic material to raised type or portions 18 formed upon a printing roll 19, having a blank pressure roll 20 arranged near and opposite the same. The rolls 17, 18, and 20 are kept suitably heated so that the thermoplastic material is maintained in the liquid condition until printed or coated upon the sheet to produce the coating 13. The sheet is passed between the rolls 19 and 20 and the travel of the sheet and the travel of the roll 19 and the location of the raised portions 18 are such that the coating 13 will be formed upon the sheet adjacent to and straddling the folding line 11, when the sheet is subsequently folded transversely upon this line. The coating 13 is applied to the inner or front face of the cover sheet 10, as explained, while the coating 13 is applied to the rear or outer face of the leaf sheet 15. The web of paper after having the coating 13 printed thereon, which instantly sets, is then fed between the pairs of printing rolls 21, whereby one or both faces of the pairs of connected leaves are printed, as is well known. The web is subsequently severed at intervals to provide the separated pairs of connected folded leaves. All leaves printed upon one web of paper contain the same subject matter, and this is true whether the leaves are cover leaves or inner leaves. When the leaves in each pair are folded, the coating 13 will be arranged to straddle the folding line, producing the reinforced coated areas. Different pairs of folded inner leaves are assembled within a pair of cover leaves to produce the magazine, and the reinforced coated areas are arranged in groups, and the coated areas in each group are in alignment, and the staple 14 is passed through all of the reinforced coated areas in each group. I contemplate applying the reinforcing coating upon all of the inner pairs of folded leaves as shown in Figure 4 or I may apply the reinforcing coating only to the center inner folded pair of leaves as shown in Figure 7 with or without the reinforcing coating applied to the pair of folded cover leaves.

If a highly volatile coating material is used, the same may be applied to the printing roll 19 by the roll 17, but elements 16, 17, 19, and 20 would not be heated.

While I have shown the coating as embodying spaced areas, the invention is not restricted to this feature as the coated area may extend throughout the entire width of the sheet.

It is to be understood that the forms of my invention herewith shown and described are to be taken as preferred examples of the same and that various changes in the shape, size, and arrangement of parts may be resorted to, and that changes in the order of the steps of the method may be made without departing from the spirit of my invention or the scope of the subjoined claims.

Having thus described my invention, what I claim is:

1. A magazine or the like, comprising a pair of back leaves having a folding line and reinforcing coatings at the folding line and spaced longitudinally thereof, pairs of inner leaves having folding lines, each inner leaf having reinforcing coatings at the folding line and spaced longitudinally of the folding line, the coatings of the several leaves overlapping to form groups, and staples connecting the several leaves and passing through the groups of coatings.

2. A magazine or the like, comprising pairs of

assembled leaves having folding lines, at least one pair of leaves having a set reinforcing coating formed of a thermoplastic material including rubber, the reinforcing coating being flexible and tough, and a staple connecting all pairs of leaves and passing through the reinforcing coating.

3. A magazine or the like comprising a pair of back leaves having a folding line and reinforcing means adjacent to the folding line, the reinforcing means consisting entirely of a plastic coating adhering to the back leaves and set before the leaves are assembled and having substantial strength, a pair of inner leaves having a folding line and reinforcing means adjacent to the folding line, the last named reinforcing means consisting entirely of a plastic coating adhering to the inner leaves and set before the leaves are assembled and having substantial strength, the coatings being in substantial alignment, and a securing element passed through the pairs of leaves and the coatings.

4. A magazine or the like, comprising a pair of back leaves having a folding line and reinforcing means upon their inner face adjacent to the folding line, the reinforcing means consisting entirely of a plastic coating adhering to the back leaves and set before the leaves are assembled, a pair of inner leaves having a folding line and reinforcing means adjacent to the folding line upon their outer face, the second named reinforcing means consisting entirely of a plastic coating adhering to the inner leaves and set before the leaves are assembled and having substantial strength, the reinforcing coatings overlapping, and an attaching element passing through the pairs of leaves and the reinforcing coatings.

5. A magazine or the like, comprising a pair of back leaves having a folding line and reinforcing means upon their inner face at the folding line, the reinforcing means consisting entirely of a plastic coating adhering to the back leaves and set before the leaves are assembled and having a substantial strength, pairs of inner leaves having folding lines, the center pair of inner leaves only having reinforcing means upon their outer face at the folding line, the second named reinforcing means consisting entirely of a plastic coating adhering to the inner leaves and set before the leaves are assembled and having substantial strength, the reinforcing coatings overlapping, and a staple passing through all the pairs of leaves and through the reinforcing coatings.

6. A magazine or the like, comprising a pair of back leaves having a folding line and reinforcing means at the folding line, the reinforcing means consisting entirely of a plastic coating adhering to the back leaves and set before the leaves are assembled, pairs of inner leaves having folding lines, at least one pair of inner leaves having reinforcing means at the folding line, the second named reinforcing means consisting entirely of a plastic coating adhering to the inner leaves and set before the leaves are assembled and having substantial strength, the reinforcing coatings overlapping, and a staple passing through all pairs of leaves and the reinforcing coatings.

7. A magazine or the like, comprising a pair of back leaves having a folding line, pairs of inner leaves having folding lines, at least one pair of inner leaves having reinforcing means at the folding line, the reinforcing means consisting entirely of a plastic coating adhering to the inner leaves and set before the leaves are assembled and having substantial strength, and attaching

means passing through all pairs of leaves and through the reinforcing coating.

8. A magazine or the like, comprising pairs of leaves having folding lines, at least one pair of leaves having reinforcing means at the folding line, the reinforcing means consisting entirely of longitudinally spaced plastic coatings, adhering to the leaves and set before the leaves are assembled and having substantial strength, and attaching elements connecting the pairs of leaves and passing through the reinforcing coatings.

9. A magazine or the like, comprising a pair of back leaves having a folding line and reinforcing means at the folding line, the reinforcing means consisting entirely of plastic coatings spaced longitudinally of the folding line and adhering to the back leaves and set before the leaves are assembled and having substantial strength, pairs of inner leaves having folding lines, the center inner leaf only having reinforcing means at the

5 folding line, the second named reinforcing means consisting entirely of plastic coatings spaced longitudinally of the last named folding line and adhering to the inner leaves and set before the leaves are assembled and having substantial strength, the coatings of the inner center leaf overlapping the coatings of the pair of back leaves, and staples passing through all pairs of leaves and through the reinforcing coatings.

10 10. A magazine or the like, comprising pairs of assembled leaves having folding lines, certain of the leaves having reinforcing means adjacent to the folding line, the reinforcing means consisting entirely of a plastic coating adhering to the leaves and set before the leaves are assembled, the set coating being flexible, tough, and having substantial tensile strength, and a staple connecting the leaves and passing through the reinforcing coating.

GEORGE HELLER.
